UNITED STATES PATENT OFFICE.

ULYSSES S. G. BROBST, OF WHITTIER, CALIFORNIA.

REFLECTOR.

Application filed March 18, 1925. Serial No. 15,902.

My invention relates to a reflector for auto and other vehicle head lamps, and the prime object thereof is to provide a device of the above character by means of which the beam of light from the lamp is so reflected as to eliminate all glare, while at the same time providing the maximum road illumination, thus providing a safe driving light which while producing the greatest road illumination will not in any way interfere with the view of the driver of an oncoming vehicle.

Another object is to provide a reflector of the above character which is interchangeable with the reflector already in the light and which can be easily and quickly positioned for use without in any way altering the head lamp with which it is to be used.

Other objects and advantages will appear hereinafter and, while I have shown and will describe the preferred form of my invention, I wish it understood that I do not limit myself to such preferred form but that various changes and adaptations may be made therein without departing from the spirit of my invention.

In the drawings accompanying and forming a part hereof:

Fig. 1 is a front elevation of my reflector.

Fig. 2 is a side elevation of Fig. 1.

Fig. 3 is a central horizontal section of Fig. 1.

Fig. 4 is a section on the line 4-4 of Fig. 1.

Referring to the drawing my reflector consists of a body 5 of a substantially parabolic configuration similar to the present type of reflector, provided centrally with a sleeve 6 through which the usual lamp socket (not shown) projects, and provided around its open end with an annular rim 7 in which are cut notches 8 the purpose of which will be obvious. The body portion of my reflector, while being substantially parabolic in shape, is specifically formed in a plurality of parallel, vertically extending panels which are slightly curved in transverse cross section, the center panels 9 and 10 of which extend the full length from the top to the bottom of body 5. The outer edges of the outermost panels 11 and 12 extend vertically from the lower edge of body 5 to a short distance above the center

of said body and are of a considerably greater width than the other panels and the outermost edges of the intermediate panels 13 and 14 extend to a point substantially half way between the outer edges of the panels 11 and 12 and the outer edges of panels 9 and 10, producing in effect, a series of vertical transversely curved panels of varying lengths, the length and curvature being so arranged that the light will be so reflected as to pass out beyond the reflector onto the roadway for a maximum distance ahead of the vehicle and at the proper height to avoid interference with the view of an approaching driver instead of being diffused into the atmosphere in all directions as with the present type of reflector.

Having described my invention, what I claim is:

1. In a lamp a ribbed reflector, the ribs thereof being curved outwardly in transverse cross section and extending perpendicularly to a horizontal plane passing through the reflector the chords of said curves being at an oblique angle to the axis of said reflector, the two adjacent center ribs extending the entire distance from top to bottom of said reflector and the remaining ribs having their upper ends tapering downwardly away from said center ribs, the outermost ribs being wider than the other ribs and being spaced from the side wall of said reflector.

2. A reflector for vehicle head lamps comprising a substantially parabolic shaped casing formed in its medial portion into a plurality of arcuate relatively shallow panels extending in planes perpendicular to a horizontal plane passing through said casing, the center panels extending along the entire wall of said casing from top to bottom, the panels at each side of said center panels tapering at their upper ends downwardly away from said center panels, the outermost panels being wider than the other panels and being spaced a distance from the side wall of said casing and the chords of curvature of said panels being tangential to the curvature of said casing.

In witness that I claim the foregoing I have hereunto set my hand this 24th day of December, 1924.

ULYSSES S. G. BROBST.
